PROTECTOR ROD FOR LOOMS

William A. Blanchard, Millbury, Mass., assignor
to Crompton & Knowles Loom Works, Worcester, Mass., a corporation of Massachusetts

Application August 17, 1948, Serial No. 44,710

6 Claims. (Cl. 139—345).

1

This invention relates to improvements in protector mechanism for a loom and it is the general object of the invention to provide an improved protector rod.

Looms are ordinarily provided with some means for arresting weaving operations if the shuttle fails to be boxed at a given time in the loom cycle. Many of these mechanisms include a lay carried protector rod having daggers for engagement with stopping mechanism. When the shuttle is properly boxed the shuttle binder exerts a force on a protector finger secured to the rod to rock the latter and thereby move the dagger out of registry with the stopping mechanism. Upon failure of the shuttle to be boxed or to emerge from the warp shed at the correct time in the loom cycle the lay moves the dagger against the stop mechanism to stop the loom. As made heretofore the protector rod has been a relatively expensive item in loom construction due largely to the fact that the rod has been made of a single elongated piece of metal to which the daggers are welded at distances along the rod corresponding to particular widths of looms.

It is an important object of the present invention to provide dagger units of improved construction which can be produced in advance and independently of the width of the looms on which they are ultimately used and subsequently welded to an intermediate rod section the length of which is determined by the width of the particular loom on which the assembled rod is to be used.

It is a further object of the invention to provide a protector rod or unit therefor including two axially aligned rod members held together by a coupling member or the like on which are mounted a number of relatively thin dagger forming elements. The latter are formed with non-circular holes to fit a non-circular part of the coupling member lying between adjacent ends of the rod members, and after the several parts are assembled they are subjected to some form of brazing or the like which in effect integrates them.

It is a more particular object of the invention to provide the aforesaid coupling member with screw threaded shanks to fit into screw threaded holes in the rod members after a series or set of dagger forming elements have been mounted on the intermediate part of the coupling member between the screw threaded shanks thereof. By reason of the screw threads it is possible to establish a tight assemblage of the parts, after

2

which they may be brazed as already mentioned.

With these and other objects in view which will appear as the description proceeds, the invention resides in the combination and arrangement of parts hereinafter described and set forth.

In the accompanying drawings, wherein a convenient embodiment of the invention is set forth,

Fig. 1 shows a side elevation of parts of a loom having the invention applied thereto, the breast beam, lay, shuttle box and part of the protector rod being shown in section,

Fig. 2 is an exploded perspective view of the several parts forming a protector rod unit prior to assembly, and

Fig. 3 is a plan view of a complete protector rod with the dagger units secured to an intermediate rod section.

Referring particularly to Fig. 1, the loom frame 10 supports a lay 11 mounted on swords 20 one of which is indicated at 12. The lay is provided with the shuttle box 13 which in the present instance has a box back 14 secured to the lay and a movable shuttle binder 15 forming the front part of the shuttle box. The shuttle S is picked back and forth across the loom and is ordinarily boxed during forward movement of the lay at such a time in the cycle of loom operations that the shuttle will be out of the warp shed designated at W. If, however, the shuttle should be tardy in its arrival at the shuttle box all or part of it may extend into the warp shed and if prompt loom stoppage is not effected under these conditions many of the warp threads will be broken.

35 Mounted on the under side of the breast beam 20 of the loom is a lever 21 associated in known manner with loom stopping mechanism and effective when moved forwardly during forward motion of the lay to stop the latter abruptly. The 40 means for operating the stopping lever 21 includes a protector rod designated herein generally at P and including an upright finger 22 secured to a rod 23 for engagement with the binder 15. A dagger 25 is also rigid with the rod 23 and means not shown herein but generally comprising a torsion spring around the rod 23 normally lifts the dagger so that the lay during its forward movement will cause engagement of the dagger and the lever 21 if there is no shuttle in 45 the shuttle box. If, however, the shuttle is boxed on time the dagger will be moved downwardly to clear the lever 21 as the lay moves toward front center, or to the left as viewed in Fig. 1. The lay is provided with bearings for rod 23 one of which 50 is shown at 24 in Fig. 1.

Except for the details of the protector rod **P** to be set forth hereinafter the mechanism already described is of usual construction and operates in the ordinary manner.

Referring particularly to Figs. 2 and 3, where in the protector rod is set forth in greater detail, it will be seen that the previously described rod **23** in effect comprises several coaxial members one of which is an intermediate section **30** connected at the opposite ends thereof to dagger units which are set forth herein as **U1** and **U2**. Since these units are alike only one of them is set forth in detail, namely, the unit **U1** at the right end of the protector rod shown in Fig. 3.

Referring particularly to Fig. 2, the unit **U1** includes right and left protector rod members **35** and **36**, respectively. The member **35** has a bore **37** therein provided with internal screw threads, and in similar manner the member **36** has a screw threaded bore **38**. These bores are preferably coaxial with their respective rod members and may either be both of the same hand or opposite hands. The end **39** of each member **35** and **36** adjacent to the threaded bore is flat and preferably perpendicular to the axis of the associated rod member.

A coupling member designated at **40** comprises an intermediate part **41** which as shown herein is substantially of square cross section. Extending in opposite directions from part **41** are coaxial shanks **42** and **43** provided with screw threads to fit the screw threads of the bores **37** and **38**, respectively. A plurality of relatively thin flat dagger forming elements **45** are provided as shown more particularly in Fig. 2, each of these elements having a flat body with an operating end or point **46** at one end thereof and a non-circular opening **47** in the other end thereof proportioned to fit the intermediate part or section **41** of the coupling member **40**. There will be enough of these flat dagger elements so that when assembled in close order they will embrace substantially the full length of the intermediate section **41**.

After the parts are provided as set forth in Fig. 2 the dagger elements will be assembled on the section **41** of the coupling member with their operating points **46** in alignment and with their holes or perforations **47**, which may be square, establishing a fairly tight fit with the intermediate section **41** of the coupling member. The rod members **35** and **36** are then threaded tightly enough on their corresponding screw threaded shanks **42** and **43** to cause the flat surfaces **39** to hold the dagger elements in close order on the coupling member. This fit may be established by having the intermediate coupling member section **41** slightly less in length than the combined width of the dagger elements, although this is not a necessary relation. It will be desirable however that the parts be so proportioned that they can be assembled in close fitting relation with each other on the coupling member with the rod members **35** and **36** either engaging or very closely adjacent to the outermost of the dagger elements.

The parts thus assembled are then placed in a furnace and brazed by an operation in which the bonding or brazing metal, such as copper or a silver alloy, flows into the spaces between the coupling member and the parts of the dagger elements and rod elements **35** and **36** closely adjacent thereto. The effect of this brazing is to unite all of the parts shown in Fig. 2 into a single dagger unit.

The dagger units may be prepared in large numbers in advance of their actual use on particular looms and stored for future use. When a protector rod is to be made for a loom of a given width two of the units can be united to the intermediate protector rod section **30** as by welding indicated at **50**. The length of the section **30** will be determined by the width of the loom. When thus made the rod can be applied to the lay in the usual manner, the protector fingers **22** being secured to the rod either before or after the welding operation depending upon whether they are to be between the two daggers or between the latter and the ends of the protector rod **23**.

From the foregoing it will be seen that the invention sets forth simple means for providing a protector rod made of similar dagger units which are united as by welding or the like to an intermediate protector rod section so that the dagger units can be made in large numbers in advance of their actual use and without reference to the width of the looms on which they are ultimately used. It will also be seen that the dagger is made of a number of flat strips which can be formed by a cheap punching operation and that these elements are assembled on a coupling member which can be readily produced automatically as a screw machine product. Furthermore, the faces **39** of the rod members **35** and **36** are united to the outer surfaces of the adjacent dagger elements in the brazing operation so that the coupling member **40** is not required to withstand all of the strain to which the protector rod is abruptly subjected when the loom must be stopped due to failure of the shuttle to box properly. By the integration or uniting of the several parts of the rod unit, particularly the coupling unit and the dagger members, a strong unit can be made from parts which are cheap and easily produced.

Having thus described the invention it will be seen that changes and modifications of the foregoing specific disclosure may be made without departing from the spirit and scope of the invention.

What is claimed as new is:

1. In a dagger unit for a loom protector rod, a pair of axially aligned rod members, a coupling member located between and extending into said rod members and formed with an intermediate section between the rod members, and a plurality of flat dagger forming elements having perforations fitting said intermediate section and located between said rod members, all of said parts of the unit being united by a bonding metal.

2. In a dagger unit for a loom protector rod, a pair of axially aligned rod members each having a screw threaded bore therein, a coupling member having oppositely extending screw threaded shanks threaded into the bores of said rod members, said coupling member having an intermediate section between said shanks, and a plurality of aligned dagger elements mounted on said intermediate section between said rod members, the rod and coupling members and dagger elements being united by a bonding metal.

3. In a dagger unit for a loom protector rod, a pair of aligned rod members each having a screw threaded bore therein, a coupling member having oppositely extending screw threaded shanks threaded into the bores of said rod members, said coupling member having an intermediate section of non-circular cross section between said shanks, and a plurality of dagger elements each formed with an operating point at one end

and a non-circular perforation in the other end thereof to fit said intermediate section of the coupling member, said elements being arranged with said intermediate section in said perforations and the operating points aligned, the rod and coupling members and dagger elements being united by a bonding metal.

4. In a dagger unit for a loom protector rod, a pair of aligned rod members each having a screw threaded bore therein, a coupling member having oppositely extending screw threaded shanks threaded into the bores of said rod members, said coupling members having an intermediate section of non-circular cross section between said shanks, and a plurality of dagger elements each formed with an operating point at one end and a non-circular perforation in the other end thereof to fit said intermediate section of the coupling member, said elements being arranged with said intermediate section in said perforations and the operating points aligned, the overall width of the dagger elements being slightly greater than the length of said intermediate section and those parts of the dagger elements surrounding said intermediate section being held together in close order by reason of the rod members being threaded tightly on their respective threaded shanks, the members and elements of said dagger unit being held together by a bonding metal.

5. In a loom protector rod, a pair of axially aligned rod members, a coupling member located between and extending into said rod members and formed with an intermediate section between the rod members, and a plurality of flat dagger forming elements having perforations fitting said intermediate section and located between said rod members, all of said parts of the unit being united by a bonded metal.
- 10 6. In a loom protector rod having an intermediate rod section and a dagger unit secured to each end of the rod section, each dagger unit comprising a pair of axially aligned rod members, a coupling member located between and extending into said rod members and formed with an intermediate section between the rod members, and a plurality of flat dagger forming elements having perforations fitting said intermediate section and located between said rod members, all of said parts of the unit being united by a bonding metal.
